(57) **CLAIM**

The ornamental design for a 2-in-1 payment module, as shown and described.

DESCRIPTION

FIG. 1 is a perspective view of a 2-in-1 payment module;

FIG. 2 is another perspective thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a view showing the state of use thereof.

The broken lines showing of portions of the 2-in-1 payment module are for the environmental purposes only and form no parts of the claimed design.

1 Claim, 5 Drawing Sheets
